UNITED STATES PATENT OFFICE

PAUL BOROWIK, OF MONAVILLE, WEST VIRGINIA

WINDOW FIXTURE

Application filed January 20, 1928. Serial No. 248,234.

This invention relates to an improved window fixture of the type constructed to accommodate the usual curtain or blind, together with one or more curtain rods for draperies, etc.

What I have endeavored to do, is to provide a structure of this class which is efficient in performance, one which will fulfill the requirements of a device of this class, one which is dependable in use, and a mechanical achievement, such as promotes economy, practicability, and one which is comparatively simple and inexpensive to the manufacturer as well as the user.

Briefly, the invention is characterized by an arrangement of structural details especially suitable to a device of this class, in that they permit the device to be readily attached to or detached from the ordinary window frame, and overcome the necessity of employing special fastenings or driving nails into the woodwork.

The features will become readily apparent from the following description and drawings.

In the drawings:—

Figure 1 is an elevational view showing the invention applied to a window frame, showing the manner in which the curtain and curtain rod are associated therewith.

Fig. 2 is a top plan view of the same.

Fig. 3 is an enlarged end view.

Fig. 4 is a vertical section through the structure seen in Fig. 3.

Fig. 5 is a perspective view of one of the details.

Fig. 6 is a perspective view of a complementary detail.

Referring now to the drawings by numerals, it will be seen that the window shade is designated by the reference character 7 and the curtain rods by the reference numerals 8.

I have also placed the numerals 9 and 10 upon the vertical and horizontal parts of the window frame respectively. The invention comprises a duplicate attaching device, and a description of one will suffice for both. Each device is somewhat in the nature of a corner cap and comprises complementary plate

sections 11 and 12 (see Figs. 5 and 6 respectively).

The upper plate 11 is provided with a flange 13 having a down-turned lip provided with teeth 14 adapted to be embedded in the top edge of the horizontal piece 10 of the window frame. This plate is provided adjacent its bottom edge with a stamped keeper 15, having a tongue 16 to serve in a manner to be hereinafter described. In addition, this plate is equipped with curtain rod brackets 17 including pairs of suspension and retaining tongues 18.

The lower plate 12 is equipped with a stamped mounting 19 for a pivoted lever 20, provided with a finger-piece 21 and carrying a swingable bail or link 22. This bail is obviously intended to embrace the mounting 19 and to swing over the keeper as shown in Fig. 4, to fasten the plates together.

As shown in Fig. 4, the lever is constructed for cooperation with a spring 23 in the cam-like manner shown. As also shown here, the mounting 19 is of hollow construction, and is so made as to provide a socket for reception of the retension tongue 16. This plate is also provided at one end with a right angularly disposed hook 24, cooperable with a stud 25 in the manner shown in Fig. 3.

In addition, it is provided with a right angular extension on the bottom edge, as shown at 26 and this is equipped with teeth 27 to become embedded in the window frame, as shown in Fig. 4. From this arrangement, it is obvious that this device comprises complementary plates disposed in edge to edge relation with toothed abutment engaging the window frame, a retaining hook, separable fasteners, for providing a quick detachable connection between the plates, as well as shade brackets 29 as shown in Fig. 1.

It is evident too, that when the plates are placed upon the corner portion of the window frame, and the finger grips 21 of the lever 20 is swung upwardly as indicated by the arrow in Fig. 3, this lifts the link or bail out of the keeper seat, permitting the plates to be separated. The reverse action of the retaining lever, however, serves to wind the

plates together, owing to the drawing action of the link and lever.

When the two devices are in place on the window frame, as shown in Fig. 1, they provide efficient means for simultaneously supporting curtain rods, shades, and brackets, and hangers.

A careful consideration of the description in connection with the drawings, will permit 10 a clear understanding of the invention to be had. Therefore, a more lengthy description is regarded unnecessary.

Having thus described my invention, what I claim as new is:—

15 A window fixture of the class described comprising a top plate adapted for disposition against a window frame, said top plate provided along its top edge with a right angularly disposed flange terminating in lateral retaining teeth, means on said top plate for the attachment of curtain rods thereto, a pair of longitudinally spaced keepers mounted on said plate adjacent the lower edge of the plate and having retaining tongues extending down beyond said edge, a complementary bottom plate also adapted for disposition against the window frame, having its upper edge in contact with the lower edge of the top plate, said lower plate being formed 25 at one end with a right angularly disposed shade roller pintle attaching and retaining hook and being provided adjacent the opposite end with a tooth equipped retaining extension, a pair of mountings on said lower 30 plate located for alinement with said keepers, said mountings being of hollow form for reception of the aforesaid retaining tongues, a lever pivotally supported on each mounting, and a link carried by the lever and embracing the mounting and engageable with the 35 complementary keeper for binding said plates together in edge to edge relation and for embedding the retaining teeth in the window frame.

40 45 In testimony whereof I affix my signature.
PAUL BOROWIK.
